UNITED STATES PATENT OFFICE

KARL SIEG, OF BROOKLAWN, NEW JERSEY, ASSIGNOR TO SAMUEL M. LANGSTON CO., OF CAMDEN, NEW JERSEY, A CORPORATION OF NEW JERSEY

ROLL EJECTING MECHANISM FOR WINDING MACHINES

Application filed April 22, 1930. Serial No. 446,204.

This invention pertains to paper winding machines of the type in which the roll of paper is supported on and rotated by a pair of drums, and it involves simple and improved means for removing the rolls of paper after they have been wound to the desired diameter.

Paper winding machines are often of such size that they form rolls of large dimensions and considerable weight, and the problem of removing such rolls from the machine is one that has presented considerable difficulty.

One of the objects of the present invention is to provide a simple, inexpensive, manually operated means of such form that it may be incorporated in new machines or added to old ones, and whereby wound rolls of paper of any size and weight may be conveniently removed from the machine.

In my improved construction I employ a manually operated roll ejecting lever of the first class which may swing about its fulcrum point and has one end adapted to engage the roll to eject the latter from the machine. As one important feature of my invention I provide adjustable supporting means for the lever fulcrum whereby the lever may be normally held out of the path of the paper, but may be brought into proper operative relation with the wound roll to be ejected irrespective of the diameter or length of the latter.

The lever is attached permanently to the machine at its fulcrum point and may have its handle end detachably connected to the machine for purposes of aiding in proper support of the lever when it is not in use, and for facilitating the movement of the lever into and out of operating position. After the lever has been brought into operating position, the handle end of the lever may be detached from its support, thus leaving it free to be rocked manually about its fulcrum point for purposes of ejecting a wound roll.

In the accompanying drawings which illustrate a practical embodiment of the invention,

Fig. 1 is a view in end elevation, partly broken away, of a paper winding machine

showing a wound roll of paper in full lines and indicating in dotted lines the movement of the lever and the paper roll as the latter is discharged from the machine, and

Fig. 2 is a fragmentary view partly in elevation, and partly in section, of the roll ejecting mechanism, viewed in a plane at right angles to the plane of Fig. 1.

In the type of winder illustrated the roll A of paper is wound on mandrel 10 while supported on a pair of winding drums 11, both of which are driven in the same direction to cause a rotation of the roll. A driven pressure roll, not shown, usually engages the upper side of the roll. As the roll increases in size the mandrel moves upwardly, but the roll continues to rest on and be supported by the winding drums 11.

When the roll increases to large diameter it is very heavy and considerable difficulty is encountered in getting the roll out of the machine as it must be lifted more or less to get it out of the groove between the drums.

In my improved construction I provide one or more, preferably two, manually operated levers 13 which are pivotally supported in the frame 14 of the machine. When the levers are not in use their upper or handle end may be connected by pins 15 to arms 16, carried by a suitable transversely extending shaft 17 mounted in the upper part of the machine, whereby they normally occupy substantially vertical positions.

Each lever is pivoted at a point adjacent to but spaced from its lower end to an adjustable fulcrum. This is shown as an arm 18 secured to a shaft 19, also mounted in the frames 14 of the machine. The lower or operating end of each lever is in the form of a wide paddle or blade 20 so that it will not cut into the paper. The blade or paddle end 20 may be made of a separate piece riveted or bolted to the body of the lever and may have ears or lugs 21 at opposite edges straddling the arm 18 and secured thereto by a pin 22 which forms the fulcrum point.

The fulcrum point 22 of the lever 13 is adjustable toward and away from a finished roll of paper for the purpose of moving the

roll engaging end or paddle 20 of the lever away from the roll to permit winding, and into engagement with the finished roll when it is desired to remove the same from the machine. For moving the fulcrum point 22 of the lever as above described means are provided for rotating the shaft 19 and thus swing the arm 18 toward or from the roll. As the shaft 19 may be somewhat inaccessible in some machines I provide it with a sprocket 25 and provide a second shaft 26 which carries a sprocket 27. Passing around the sprockets 25 and 27 is a driving chain 28. By this means the shaft 19 may be rotated and the fulcrum shifted by rotating the shaft 26.

For rotating the shaft 26 there is provided on the shaft a housing 29 having a pinion 30 mounted therein on a stub shaft 20. Keyed to the shaft 26, and meshing with the pinion 30 is a gear 32, and keyed to a hub extension 33 of the sprocket 27 is a gear 34, which also meshes with the pinion 30. The gears 32 and 34 have slightly different teeth; the shaft 26 is non-rotatable; and the hub extension and sprocket are loose on the shaft. The housing 29 may be rotated by means of a suitable handle 35 whereby the pinion 30 will travel around the stationary gear 32 and will be driven thereby. The rotation of the pinion 30 serves to drive the gear 34 and the sprocket 27 at low speed because of the fact that the gears 32 and 34 do not have the same number of teeth. There may be a difference of only one tooth. By this construction of gears and sprocket and chain drive the shaft 19 may be rotated to move the fulcrum point of the lever slowly and accurately to a position where the roll engaging end of the lever engages the surface of the roll to be ejected.

To prevent rotation of the housing 29 in a reverse direction during operation of removing the roll from the machine, a pawl 36 is secured to that portion of the handle 35 which extends inwardly of the housing 29. The nose of the pawl is normally maintained in engagement with the teeth of the gear 32 by a spring 37. The pawl may be secured to the handle so that it may be disengaged from the teeth of the gear wheel 32 by rotating the handle about its axis, when it is desired to rotate the housing 29 in the opposite direction to move the roll engaging ends 55 of the lever to a position in which it will not interfere with the winding of a roll. The chain 28 may be kept taut by a suitable idler 38 having an eccentric mounting to provide adjustment.

60 The device operates in the following manner:

When it is desired to remove a formed roll of paper, such as A, the crank handle 35 is grasped and the housing 29 rotated around the shaft 26, and through the medium of the

gears 30, 32 and 34, the sprocket 27 is driven, which through the medium of the chain 28, drives the sprocket 25. Driving the sprocket 25 rotates the shaft 19, moving the fulcrum point 22 and the roll engaging ends of the lever 13 against the formed roll of paper. During this movement the lever is suspended from and guided by the arms 16. The lever 13 is then disconnected from the arm 16 by removing the pin 15 so that the lever is free to rock about its fulcrum point. The operator grasps the lever 13 near its upper ends and rocks it about its fulcrum point, causing the lower ends of the lever to force the roll of paper from its position between the winding drums 11, to a suitable support which may be in the form of a table or the like, not illustrated.

Due to the fact that the fulcrum is near the lower end of the lever and the handle end is long, great power may be brought to bear. It is also important that the operator may bring the full weight of his body to bear in pulling the lever down. Two men may grasp and pull on the lever at the same time, if necessary.

After the roll has been removed from the machine, the lever is again attached at its upper end to its supporting arm 16. The crank handle 35 is oscillated to disengage the pawl 36 from the teeth of the gear 32 and the housing 29 is rotated to move the arm 18, the fulcrum point 22, and the roll engaging end of the lever to a point where it will not interfere with the subsequent winding of another roll of paper.

By pivotally connecting the upper end of the lever with the swinging arm 16, the pin 15 serves as the fulcrum about which the lever is moved into and out of roll engaging position. It also forms means which hold the lever against free swinging movement in the machine when not in use. Inasmuch as the bulk of the weight of the lever 13 is carried by its fulcrum point 22, the arm 16 to which the lever is pivotally mounted, may be of relatively light construction, since this arm is not intended to participate in the operation of removing the finished rolls of paper from the machine by the lever 13, and is therefore subjected to no great amount of strain.

I have illustrated a pair of levers 13. As their upper and lower ends are connected to parallel shafts they may be adjusted along the shafts to bring them adjacent to the ends, the middle or other portion of the roll irrespective of its length. The machine is usually provided with a slitter for trimming or slitting the paper, but this forms no portion of the machine and has not been illustrated.

It is to be understood that the invention is not to be limited to the specific form herein illustrated, but may be practiced in such

other forms as rightfully fall within the scope of the appended claims.

Having thus described my invention, what I claim as new and desire to secure by Letters Patent is:

1. A device for ejecting wound paper rolls from paper winding machines, comprising a lever, a support for one end of said lever, a fulcrum for the intermediate portion of said lever, and means for adjusting the fulcrum to bring the other end of the lever into operative relation with a wound roll of paper.
2. A paper winding machine having a lever, a member for detachably supporting one end of said lever, and means for swinging said lever about said member to bring it into operative relation with a wound roll of paper, said means including a fulcrum about which the lever may swing in ejecting a roll upon the disengagement of the lever from said member.
3. A paper winding machine having a roll ejecting lever, detachable means for supporting said lever at its upper end, a fulcrum to which said lever is pivotally attached near its lower end, and means for adjusting the position of said fulcrum to move the lower end of said hand lever into and out of operative engagement with a wound roll of paper.
4. A paper winding machine including a manually operated roll ejecting lever, a pivotal support for one end of said lever, a fulcrum for an intermediate portion of said lever and about which the lever swings in roll ejecting operation, and means for moving said lever about said support and shifting the fulcrum to move its work engaging end into and out of operative relation with a wound roll of paper.
5. A paper winding machine having a roll ejecting lever, an adjustable fulcrum for said lever, means for adjusting said fulcrum to move said lever into and out of operative relation with a wound roll of paper, and means independent of the fulcrum and detachably connected to said lever for supporting said lever in the machine.
6. A paper winding machine having a pair of drums for supporting a roll of paper, a pair of shafts each having an arm, a lever having one end pivoted to one arm, and an intermediate portion pivoted to the other arm, the other end of the lever being disposed adjacent to the roll, and means for swinging one of said arms to move said last mentioned end of the lever in respect to said roll.
7. A paper winding machine having a pair of drums for supporting a roll of paper, an arm having one end pivoted adjacent to one of said drums, a roll ejecting lever having an intermediate portion pivoted to said arm, and an operating end adjacent to one of said drums, means for swinging said arm, and means for pivotally supporting the opposite end of the lever.

8. A paper winding machine having a pair of drums for supporting a roll of paper, a pair of parallel shafts, one disposed adjacent to one of said drums and having an arm, a roll ejecting lever having an intermediate portion pivoted to said arm, and an operating end adjacent to one of said drums, and means for supporting the opposite end of the lever, said means being detachable from the lever, whereby the upper end may serve as a handle for swinging the lever on said arm as a fulcrum.

9. A paper winding machine having a pair of drums for supporting a roll of paper, a pair of transverse shafts, each having an arm, a lever pivotally connected to both of said arms, said arms being slideable along their respective shafts to position the lever in the desired position along the length of the roll.

10. A paper winding machine including a pair of roll supporting drums, a roll ejecting lever normally disposed substantially vertical, a shaft having an arm pivotally connected to the upper end of the lever, a second shaft having an arm pivotally connected to the lever intermediate of its ends, and means for rotating one of said shafts to swing said lever.

11. A paper winding machine including a pair of roll supporting drums, a roll ejecting lever normally disposed substantially vertical, a shaft having an arm pivotally connected to the upper end of the lever, a second shaft having an arm pivotally connected to the lever intermediate of its ends, and means for rotating the second mentioned shaft to swing said lever, said lever being detachable from said first mentioned arm to permit further swinging movement of the lever.

12. A paper winding machine having a pair of roll supporting drums, a pair of shafts parallel thereto and each having an arm, a lever having one end pivotally connected to one of said arms and its intermediate portion pivotally connected to the other arm, and speed reducing gearing for oscillating said last mentioned arm.

13. A paper winding machine having a pair of roll supporting drums, a pair of shafts parallel thereto and each having an arm, a lever having one end pivotally connected to one of said arms and its intermediate portion pivotally connected to the other arm, speed reducing gearing for oscillating said last mentioned arm to bring the other end of the lever into engagement with the roll, and means for preventing return movement of said lever during the swinging of the lever about said last mentioned pivotal connections while ejecting the roll.

14. A paper winding machine having means for supporting and rotating a roll of paper being wound, a pair of shafts, a roll ejecting lever, an arm on one of said shafts and pivotally connected to one end of said

lever, an arm on the other shaft pivotally connected to the lever intermediate of the ends of the latter, and means for oscillating said last mentioned arm.

- 5 15. A paper winding machine having means for supporting and rotating a roll of paper being wound, a pair of shafts, a roll ejecting lever, an arm on one of said shafts and pivotally connected to one end of said lever, an arm on the other shaft pivotally connected to the lever intermediate of the ends of the latter, means for oscillating said last mentioned arm to bring the other end of the lever into engagement with the roll, and
10 15 means for preventing return movement of said arm, whereby the pivotal connections to said arm form a fixed fulcrum about which said lever may swing during said roll ejecting movement.
- 20 16. A paper winding machine having means for supporting and rotating a roll of paper being wound, a lever having a comparatively wide roll engaging end and an upwardly extending handle portion, a fulcrum intermediate of the ends of said lever, and means for adjusting said fulcrum toward and from the roll.

- 25 30 17. A paper winding machine having means for supporting a roll of paper being wound, a lever normally positioned substantially upright when inoperative, and having a lower roll engaging end, a pivotal support for the upper end of the lever, and means engaging the lever intermediate of its ends 35 for swinging the lever to move the lower end in respect to the roll.

- 40 45 18. A paper winding machine having means for supporting and rotating a roll of paper, a roll ejecting lever, a pivotal support for one end of said lever, a shaft having a member carried thereby and operatively connected to said lever intermediate of the ends of the latter, a rotatable driving member, and speed reducing gearing between said last mentioned member and said first mentioned member for oscillating the latter.

- 50 55 19. A paper winding machine having means for supporting and rotating a roll of paper, a roll ejecting lever having a comparatively wide roll engaging end section provided with a pair of lugs, a shaft having an arm pivotally secured between and to said lugs, and means for swinging said arm.

- 60 65 20. A device for ejecting wound paper rolls from paper winding machines, comprising a lever, a fulcrum for said lever, and rotatable means for selectively moving said fulcrum towards or away from the wound roll of paper.

- 60 Signed at Camden, in the county of Camden, and State of New Jersey, this 17th day of April, A. D. 1930:

KARL SIEG.
